(57) **CLAIM**

The ornamental design for a travel sized compact office camera apparatus with two independently adjustable cameras and an image preview screen, as shown and described.

DESCRIPTION

FIG. 1 is a perspective view of an office camera in a first configuration.

FIG. 2 is a top view of the office camera shown in FIG. 1 in the first configuration.

FIG. 3 is a bottom view of the office camera shown in FIG. 1 in the first configuration.

FIG. 4 is a front view of the office camera shown in FIG. 1 in the first configuration;

FIG. 5 is a rear view of the office camera shown in FIG. 1 in the first configuration.

FIG. 6 is a left view of the office camera shown in FIG. 1, the right view being a mirror image of the left view.

FIG. 7 is a perspective view of the office camera in a second configuration.

FIG. 8 is a perspective view of the office camera in a third configuration.

FIG. 9 is a top view of the office camera shown in FIG. 7 in the second configuration.

FIG. 10 is a bottom view of the office camera shown in FIG. 7 in the second configuration.

FIG. 11 is a front view of the office camera shown in FIG. 7 in the second configuration.

FIG. 12 is a rear view of the office camera shown in FIG. 7 in the second configuration; and,

FIG. 13 is a right view of the office camera shown in FIG. 7 in the second configuration, the left view being a mirror image of the right view.

The broken lines shown in the drawings are provided for environmental purposes and form no part of the claimed design.
